(57) **CLAIM**

The ornamental design for a vehicle body for a 4 wheel bike and/or car chassis, as shown.

DESCRIPTION

FIG. 1 is a perspective view taken from the right rear of a vehicle body designed for a 4-wheel chassis for pedal, electric or gas cars and/or bikes showing my new design; FIG. 2 is a left side view, thereof view.

FIG. 3 is a right side view, thereof

FIG. 4 is a front view, thereof; and,

FIG. 5 is a rear view, thereof.

The broken line showing of wheels is for illustrative purposes only and forms no part of the claimed design.
